MILK CARTON HOLDER

Everett R. Mitchell, Missoula, Mont.

Application January 16, 1956, Serial No. 39,776

Term of patent 14 years

(Cl. D58—26)

FIG. 1

FIG. 2

FIG. 3

FIG. 4

FIG. 5

Fig. 1 is a perspective view of a milk carton holder showing my new design;

Fig. 2 is an elevational view taken from the left side of Fig. 1;

Fig. 3 is a rear elevational view thereof;

Fig. 4 is a front elevational view thereof; and

Fig. 5 is a top plan view thereof.

I claim:

The ornamental design for a milk carton holder, substantially as shown.
